UNITED STATES PATENT OFFICE.

JAMES F. TIERNEY, OF INDIANAPOLIS, INDIANA.

TOY-PROPELLING MEANS.

1,257,151.

Specification of Letters Patent. Patented Feb. 19, 1918.

Application filed September 24, 1917. Serial No. 192,921.

To all whom it may concern:

Be it known that I, JAMES F. TIERNEY, a citizen of the United States, residing at Indianapolis, in the county of Marion and State of Indiana, have invented a new and useful Toy-Propelling Means, of which the following is a specification, reference being had to the accompanying drawings and to the letters and figures of reference marked thereon.

This invention relates to means to be used with water for propelling various types of movable structures that may operate in or above a body of water, the invention having reference more particularly to means for propelling the smaller classes of structures commonly known as toys, such as boats, merry-go-rounds, or other vehicles that may be guided on tracks.

An object of the invention is to provide simple and inexpensive means for propelling structures in or above water, without involving complicated machinery or mechanism requiring more or less expert attention for operation and repairs with consequent expense.

Another object is to provide improved toy-propelling means that may be substantially constructed and not be liable to become impaired because of long use or lack of care and careless handling.

A further object is to provide improved toy-propelling means which shall be so constructed as to be efficient, not dangerous to the unskilled and which shall be durable and economical in use.

With the above-mentioned and other objects in view, the invention consists in a double-action engine adapted to utilize water as a means of propulsion, all of novel construction and arrangement; and, the invention consists also further in the novel parts and combinations and arrangements of parts as hereinafter described and set forth in the appended claims.

Referring to the drawings,—Figure 1 is a side elevation of a boat, partially broken away, provided with the improved propelling means; Fig. 2 is a rear elevation of the boat equipped with the invention; Fig. 3 is a side elevation of the engine or principal structure of the improved propelling means constructed in a form suitable for application to a boat or other vehicle; Fig. 4 is a top plan of Fig. 3 partially broken away; Fig. 5 is a section on the line V—V on Fig.

3; Fig. 6 is a longitudinal central section of the principal elements of the engine; Fig. 7 is an elevation, partially broken away, of a merry-go-round provided with the invention to illustrate the propelling means as applied to a structure guided to move above a body of water; Fig. 8 is a top plan of Fig. 7 partially broken away; Fig. 9 is an inverted plan view of the rotary platform or turn table of the merry-go-round provided with the improved engine; and, Fig. 10 is a plan of the improved engine slightly modified to adapt it for actuating a rotary structure.

On the different figures of the drawings, like reference characters indicate corresponding elements or features of construction herein referred to.

One of the elements necessary to the operation of the improved propelling means is a body of water 1 and in some cases the invention is applied to a boat to float in the water, a simple form of boat sufficient to an understanding of the invention being illustrated and comprising a hull 2 provided with a keel 3 and also a deck 4 having a removable section or hatch 5. The hull has a horizontal lamp-holder 6 therein on which a lamp 7 is removably supported so that it may be removed for re-filling after removing the section 5 of the deck, the lamp having a suitable burner 8. The lamp and burner may be such as is commonly provided for the burning of alcohol for heating purposes.

The improved engine comprises a suitable boiler which preferably is constructed as a hollow cylinder so as to constitute a combined boiler and cylinder structure 9, provided with suitable closures or heads 10 and 11 in the opposite ends thereof. As preferably constructed, the closures are made separately as heads and secured to the cylinder, one head having a central aperture or opening to constitute a duct 12 and having a valve seat 13 at the inner end of the duct. The opposite head 11 has a similar duct 14 and a valve seat 15. A suitable valve is provided which is adapted to automatically act to close the ducts alternately, the preferred form of valve being a spherical valve 16 that is nearly as large in diameter as the interior of the cylinder 9 in which the valve freely rolls between the valve seats. Two conducting pipes are provided, one pipe having a straight portion 17 that is secured to

the head 10 to form communication with the duct 12, the other pipe having a straight portion 18 that is connected with the head 11 to form communication with the duct 14. 5 The first mentioned one of the pipes has a return-bend or crook portion 19 extending from the straight portion 17 and from which extends a reach portion 20 in proximity to one side of the cylinder. In the present case, 10 the cylinder is horizontally supported in the boat with its middle portion above the burner 8 of the heating lamp, the boiler or cylinder 9 being above the level of the body of water. In such case the pipe has a down- 15 wardly extending inclined portion 21 continuing from the pipe portion 20 and through the bottom of the hull of the boat at one side of the keel, the pipe having a terminal portion 22 extending from the inclined portion so as to be approximately 20 horizontal. The other pipe comprises an inclined portion 23 extending from the straight portion 18 and a terminal portion 24 extending from the inclined portion, the latter extending through the bottom of the 25 hull at the opposite side of the keel. The terminal portions of the pipes are arranged conveniently close together so as to discharge rearwardly with respect to the boat and 30 preferably the pipes are secured to the keel by means of clamps 25 and 26.

As explaining the application of the invention to a structure that is guided above a body of water, a merry-go-round is shown 35 which comprises a tank having a bottom 27 and a circular side wall 28 to hold a body of water 1', the upper portion of the wall having a circular track 29 above which a rotary platform or turn table 30 is arranged and 40 provided with a center shaft 31 that extends into the water and is centered on a center plate 32 on the bottom of the tank, the under side of the platform being provided with rollers 33 to run on the track when the table 45 is slightly tilted. The platform or turn table is suitably equipped with seats or articles 34 characteristic of the well-known amusement device. The under side of the platform 30 carries a suitable holder 35 which removably 50 supports a lamp 7' having a burner 8' which is readily accessible when the platform is lifted from the tank. The cylinder 9' is supported under the platform by means of hangers 36 with the middle portion of the 55 cylinder above the lamp burner. One end of the cylinder is provided with a conducting pipe having the straight portion 17, the return-bend 19 and reach portion 20, and for the present purpose the pipe has a down- 60 wardly extending laterally curved portion 37 continuing from the pipe portion 20 and from which extends a terminal portion 38. The opposite end of the cylinder is provided with a conducting pipe having the 65 straight portion 18 from which extends a

downwardly extending curved portion 39 from which a terminal portion 40 extends. The terminal portions of the pipes are brought conveniently close together and arranged so as to discharge conveniently 70 close to the side wall of the tank and in one and the same direction, so as to cause a movement of the turn table in the opposite direction. Preferably the terminal portions of the pipes are secured to a bracket 41 75 which is secured to the platform 30 and maintains the ends of the pipes below the surface of the water.

In practical use, a flame is produced at the burner of the heating lamp and causes 80 the boiler to become heated. The valve becomes seated so as to close one of the conducting pipes, and the water in the cylinder becoming heated may be partially converted into vapor or steam and consequently is expanded and forced out through the opposite conducting pipe so as to produce a pulsation as the water is ejected from the pipe into the surrounding body of water, re-action taking place in the cylinder or boiler which 85 brings the valve to the opposite seat and permits water to flow in behind it through the other pipe, the water becoming heated as in the first instance and subsequently ejected through the pipe in which it was 90 admitted, the repeated alternating pulsations affording sufficient force to propel the structure forward.

Having thus described the invention, what is claimed as new is—

100

1. Toy-propelling means including a boiler, two conducting pipes connected with different portions of the boiler, means for heating the boiler, and a valve movable in the boiler to automatically act to close or open the two conducting pipes alternately.

105

2. Toy-propelling means including a pressure-retaining boiler having two conducting pipes extending from different portions of the wall thereof and to a terminal position and arranged to discharge in one direction, and a valve movable in the boiler to automatically control the discharge from the boiler through the pipes alternately.

110

3. Toy-propelling means including a hollow cylinder, two conducting pipes connected with the opposite ends respectively of the cylinder and extending to a terminal position to discharge in one direction, each pipe being provided within the cylinder 115 with a valve seat, and a spherical valve in the cylinder to roll to the valve seat of each one of the pipes alternately.

120

4. Toy-propelling means including a hollow cylindrical boiler having two conducting pipes connected therewith, the inner end of each pipe being provided within the boiler with a valve seat, the outer ends of the pipes being arranged to discharge in one direction, and a spherical valve movably 125 130

guided in the boiler between the valve seats to close either one of the pipes.

5. Toy - propelling means including a boiler having two openings and valve seats at the openings, a valve movably guided in the boiler between the valve seats and adapted to close either one of the openings, and two pipes connected with the openings respectively and having their outer ends in 10 coöperative arrangement to discharge in one and the same direction.

6. Toy - propelling means including a hollow cylinder having a head in each of its two ends, each head having an opening and 15 a valve seat at the inner end of the opening, two pipes connected with the openings in the heads respectively and extending therefrom in opposite directions, one of the pipes having a return-bend and extending thence 20 in the direction of the remaining one of the pipes, the outer ends of the pipes being arranged to discharge therefrom in one direction, and a spherical valve movably guided in the cylinder between the heads thereof 25 to the valve seat and close either one of the openings in the heads.

7. A toy comprising a movable body to be associated with a body of water, a hollow cylinder horizontally supported by the movable body, two conducting pipes connected 30 with the opposite ends respectively of the

cylinder, each pipe being provided within the cylinder with a valve seat, one of the pipes extending to a position to terminate in the water, the remaining one of the pipes 35 having a return-bend from which it extends also to said position, the terminal ends of the pipes facing in one direction to coöperate in propelling the movable body, a lamp supported by the movable body below the 40 middle portion of the cylinder, and a spherical valve in the cylinder to roll alternately to each one of the valve seats.

8. The combination with a toy structure adapted to be movably guided in association 45 with a body of water, of a boiler stationarily connected to the toy structure and provided with a heater for converting water into vapor in the boiler, two conducting pipes connected with different portions of the wall 50 of the boiler to conduct the water alternately into and out of the boiler, and means automatically acting on operation of the heater to control the flow of the water 55 through the pipes.

In testimony whereof, I affix my signature in presence of two witnesses.

JAMES F. TIERNEY.
